US00D758745S

(12) **United States Design Patent**
Blakely et al.

(10) **Patent No.:** **US D758,745 S**
(45) **Date of Patent:** **** Jun. 14, 2016**

(54) **LOWER BODY GARMENT WITH OUTER SURFACE ORNAMENTATION**

(71) Applicant: **Under Armour, Inc.**, Baltimore, MD (US)

(72) Inventors: **Kyle Sanders Blakely**, Baltimore, MD (US); **Peter Fong**, Vancouver (CA); **Julian McClain**, Baltimore, MD (US)

(73) Assignee: **Under Armour, Inc.**, Baltimore, MD (US)

(**) Term: **14 Years**

(21) Appl. No.: **29/490,380**

(22) Filed: **May 9, 2014**

Related U.S. Application Data

(62) Division of application No. 29/448,227, filed on Mar. 11, 2013, now Pat. No. Des. 704,455.

(51) **LOC (10) Cl.** **05-05**

(52) **U.S. Cl.**

USPC **D5/56**; D2/742

(57) **CLAIM**

The ornamental design for a lower body garment with outer surface ornamentation, as shown and described.

DESCRIPTION

The sole FIGURE is a plan view of a lower body garment with outer surface ornamentation showing our new design.

The broken lines surrounding the lower body garment with outer surface ornamentation in the sole figure represent the boundaries of the claim and form no part thereof.

1 Claim, 1 Drawing Sheet
